UNITED STATES PATENT OFFICE.

JOSEPH C. DONNELLY, OF PHILADELPHIA, PENNSYLVANIA, ASSIGNOR TO THE DIAMOND MATCH COMPANY, OF NEW YORK, N. Y., A CORPORATION OF ILLINOIS.

MATCH-MAKING MACHINE.

SPECIFICATION forming part of Letters Patent No. 727,308, dated May 5, 1903.

Application filed April 7, 1900. Serial No. 11,919. (No model.)

To all whom it may concern:

Be it known that I, JOSEPH C. DONNELLY, a citizen of the United States, residing in the city and county of Philadelphia and State of Pennsylvania, have invented certain new and useful Improvements in Match-Making Machines, of which the following is a full, clear, and exact description, reference being had to the accompanying drawings, forming a part 10 of this specification.

This invention relates to match-machines, its object, stated generally, being the provision of novel and efficient mechanism operating in respect to a continuously-moving splint 15 or match carrier in a manner to act upon and expel splints or matches from the carrier, as will be hereinafter fully set forth and claimed.

In the annexed drawings I have illustrated the preferred embodiment of my invention; 20 but it is to be understood that I do not limit myself to the specific construction herein shown and described, as in the light of my invention the mechanisms may be modified without departing from the fair spirit of the 25 invention.

Referring to the drawings, Figure 1 is a sectional elevation of ejecting mechanism embodying my invention, showing the adjacent portion of the carrier and the actuating-gear- 30 ing therefor. Fig. 2 is a vertical section as on the line *xx* of Fig. 1. Fig. 3 is a transverse section as on the line *yy* of Fig. 1. Fig. 4 is a sectional detail of the lower end of the punch-head and the adjacent part of the carrier. Fig. 5 is a view of the under side of the 35 punch-head.

A represents a carrier which may comprise a plurality of perforated plates of usual construction linked together or otherwise connected. The connections between the plates 40 may comprise slotted links—such, for example, as indicated at *a*—to permit relative independent movement of the plates within limits at certain stages of their travel; but neither such mode of connection nor the means for independently moving the plates 45 relative to each other concerns the present invention. The carrier is supported and guided upon rail-sections 1, bolted or otherwise secured to a suitably-located frame 2.

Upon this frame and constituting, in effect, parts thereof are end heads 3, carrying boxes 4, in the bearings of which is journaled a transverse shaft 5, to which continuous motion is imparted from a suitable source of power. This shaft is geared through a suitable gear-train with suitably-disposed racks 6 on the under side of the carrier, so as to impel the latter positively and continuously. For this purpose there are affixed on the respective ends of the shaft 5 pinions 7, that gear with spur-wheels 8, fast on stud-shafts 9, journaled in the end heads, each of the latter shafts being provided with a pinion 10, which gears with a spur-wheel 11, fast on a 65 shaft 12, journaled below the carrier. On the latter shaft is a pinion 13, which coacts with two laterally-disposed pinions 14, that gear with the adjacent rack or racks on the carrier.

Mounted in horizontal guideways 15 in the end heads are slide-blocks 16, provided with appropriate orifices in which are fitted eccentrics or cams 17 on the shaft 5, to the end that said blocks will be reciprocated horizontally during the continuous rotation of the shaft. These blocks are provided on their upper and lower edges with vertical extensions 18, bearing lateral studs or rollers 19, which are fitted to vertical guideways 20 in 80 the members 21 of a cross-head 22, lying directly above the path of the carrier.

In each end member is a horizontal guideway 23, to which is fitted a block 24 of a length slightly less than that of the guideway. In 85 this block is an orifice 25, in which is seated an eccentric or cam 26 on the shaft 5, to the end that during the rotation of the latter the block and therewith the cross-head will be raised and lowered, such movement of the 90 cross-head, plus the concurrent horizontal movement imparted thereto by the slide-blocks 16, causing the head to describe a substantially elliptical path. On the lower edge of the head are two rows of studs 27, which 95 extend from opposite sides of the carrier to the median line thereof. One of the rows is in advance of the other, and they are each so disposed in the present instance as to correspond in number and position with one-half 100

of a transverse row of perforations in the carrier and are adapted to register therewith.

The parts above described are so timed that the punch-head and carrier operate in synchronism—that is to say, during the continuous movement of the carrier past the head the latter in descending moves in the same direction and at the same speed as the carrier, the punches at the same time acting upon the splints or matches in the corresponding perforations in the carrier, and the head in ascending returns to its original position for the repetition of its action upon the succeeding rows of splints or matches in the carrier.

It is to be understood that the carrier may comprise a single perforated plate or a series of such plates separate and independent of each other; also, that when my invention is embodied in a match-machine having an endless carrier such carrier is supported and driven by the usual guide-wheels and gearing at various points throughout its traverse.

25 The perforations in the respective plates herein illustrated are formed in equidistant parallel rows, whereof the end rows are preferably so disposed that when two adjoining plates are end to end the distance between 30 the adjacent end rows of the respective plates is that between adjacent rows in the body of the plate.

Each portion of the plate or carrier provided with a row of perforations may be designated an "integral perforated section" in contradistinction to those constructions in which each section of the carrier is composed of plural members between which the splints or matches are clamped by lateral pressure 40 and from which such splints or matches are discharged by the separation of the said members.

It is to be understood that the term "splints" or "matches" is used herein to include rigid strips provided or not with ignitable composition, for the reason that the invention, broadly considered, resides in and is characterized by ejecting mechanism having a compound reciprocal operation, by 50 which it is caused to act progressively upon and only upon those ends of the splints, &c., which are held in carrier apertures or openings whose walls are of fixed and unvarying size during the continuous (non-intermittent) 55 movement of the carrier past said mechanism. Thus the stopping of the carrier during the operation of the ejecting mechanism upon succeeding rows of splints or matches is avoided, and in consequence speed and 60 ease of operation are attained.

Upon the cross-bars of the frame 2 is preferably disposed a series of longitudinal plates 28, which perform the function of thrust-bars to support the carrier and counteract the 65 pressure thereon during the impact of the punching mechanism.

I claim as my invention—

1. In a match-machine, the combination with a continuously-moving carrier comprising integral perforated sections for the 70 matches, of means carrying devices for engaging the matches to remove them from the carrier, and means for giving said first-mentioned means a reciprocating movement in the direction of motion of the carrier and back 75 again, substantially as and for the purpose described.

2. In a match-machine, the combination with a continuously-moving carrier having rows of match-holding apertures or openings 80 whose walls are of fixed or unvarying size while the matches are being removed, of means carrying devices for engaging the matches to remove them from the carrier, and means for giving said first-mentioned 85 means a reciprocating movement in the direction of motion of the carrier and back again.

3. The combination with a splint-carrier, and means for continuously moving the same, 90 of a plunger for ejecting splints from said carrier, a shaft, cams thereon, and connections between said cams and the plunger whereby the plunger is actuated in a substantially elliptical or curvilinear path.

4. The combination with a splint-carrier, and means for continuously moving the same, 100 of a plunger for ejecting splints from said carrier, a shaft, cams thereon, connections between said cams and the plunger, whereby 105 the plunger is actuated in a substantially elliptical path, and gearing between said shaft and the carrier-moving means whereby the carrier and plunger are actuated synchronously.

5. The combination with a splint-carrier, and means for continuously moving the same, 110 of a plunger for ejecting splints from the carrier, a shaft, slide-blocks, guides therefor, eccentrics, or cams, on said shaft coacting 115 with said blocks, connections between said blocks and the plunger, blocks fitted to guideways in the plunger, and eccentrics or cams on said shaft, coacting with the latter blocks, whereby a rising and falling as well as a longitudinal motion is imparted to said plunger.

6. The combination with a splint-carrier, and means for continuously moving the same, 120 of a plunger for ejecting splints from the carrier, and supports provided with horizontal guideways, slide-blocks fitted to said guideways and having a vertical sliding connection with said plunger, a shaft, eccentrics or cams thereon fitted to said slide-blocks, slide-blocks fitted to guideways in the plunger, and eccentrics or cams on said shaft fitted to the latter slide-blocks.

In testimony whereof I have hereunto affixed my signature in the presence of two subscribing witnesses.

JOSEPH C. DONNELLY.
